[21] Appl. No.: 595,008

Primary Examiner—A. Hugo Word

Assistant Examiner—R. Seifert

Attorney, Agent, or Firm—Richard C. Litman

[22] Filed: Oct. 10, 1990

CLAIM

The new ornamental design for shirt retaining strap set,
as shown and described.

DESCRIPTION

FIG. 1 is a top plan view of the shirt retaining strap set showing my new design;

FIG. 2 is a rear perspective view thereof;

FIG. 3 is a left side elevational view thereof;

FIG. 4 is a bottom plan view thereof; and,

FIG. 5 is an end elevational view of one of the straps.
